UNITED STATES PATENT OFFICE.

WILLIAM GILMOUR, OF KIDDERMINSTER, ENGLAND, ASSIGNOR TO HENRY JECKS DIXON & SONS, OF SAME PLACE.

DESIGN FOR CARPET.

Specification forming part of Design No. 6,336, dated January 7, 1873.

To all whom it may concern:

Be it known that I, WILLIAM GILMOUR, of Kidderminster, in the county of Worcester, in England, have invented a new and original Design for Carpets; and I do hereby declare that the following is a full, clear, and exact description thereof, which will enable others skilled in the art to make and use the same, reference being had to the accompanying photographic illustration forming part of the specification.

This design consists of a figure formed by three bars or parallelograms profusely ornamented with various figures, and placed side by side. The middle bar is longer than the lateral ones, and is embellished at the ends with scroll-work. Each of the smaller bars has a semi-oval projection on the outer side, and these sides, together with the ends of the figures, are ornamented with scroll-work. The three bars are connected by four ovals, so as

to form a shield. The figures thus formed are coupled together, being placed with their ends pointing toward each other, and separated, but by a small space. Between each couple is a diamond-shaped figure, having a fancy border, and a small light-colored figure in the center.

The ground of this carpet is of a light color, and over it trails a creeping vine in full bloom, and a line of small figures of various patterns runs between and parallel with the principal figures above described.

I claim as my invention—
The design for carpets, as shown.

WILLIAM GILMOUR.

Witnesses:

JAMES MORTON,
Solicitor, Kidderminster.
CHARLES FROST,
Clerk to Mr. Morton.
